STOKER CONTROL SYSTEM

Ernest T. Selig, Jr., Kansas City, Mo.

Application September 23, 1940, Serial No. 357,964

11 Claims. (Cl. 110—72)

This invention relates to a control system for automatic stokers, and the main object of the invention is to devise a control system which will substantially reduce and/or eliminate the blowing of ash from the stoker. This application is, in part, a continuation of my copending application Ser. No. 163,870, filed September 14, 1937, now Patent No. 2,218,859 dated October 22, 1940.

In domestic heating systems using coal as a fuel and employing automatic means for intermittently supplying fuel to the burner, the fuel burns down during the shut-down periods, leaving a ring of ash around the burner or tuyère, and, upon starting up again, the blower supplying air to the burner blows the ash out of the burner, and this ash, passing through cracks in the combustion chamber and smoke pipe, passes out into the room and becomes a source of considerable annoyance. The fine ash that is carried out of the furnace in the manner described is commonly known as "fly-ash."

According to my invention, I substantially eliminate the difficulty of "fly-ash" by arranging the control system so that upon starting up after each shut-down period, the full blast of air is not supplied immediately upon starting of the fuel-feed device, but means are provided to delay the application of the full blast of air for a time sufficient to allow the fuel-feeding mechanism to feed enough coal to the burner to displace the ash from directly above the air nozzle or tuyère. In this manner, the fly-ash is removed from the direct path of the air blast supplied to the burner, and it drops down into the ashpit without being blown up into the combustion chamber.

A number of embodiments of my invention are illustrated in the accompanying drawing, in which:

Figure 1 is a diagrammatic view illustrating my invention applied to a coal-burning automatic stoker of a type commonly known;

Figure 1a is a diagrammatic view on an enlarged scale showing the arrangement of the time-delay device for operating the damper in Figure 1;

Figures 1b and 1c are further modifications of the time-delay device for operating the damper;

Figure 2 illustrates a modified form of control in which the air is controlled by a damper in the blower outlet duct;

Figure 3 illustrates a modified form of control in which the damper is operated by an electromagnet which in turn is controlled by the time-delay device; and

Figure 4 illustrates a modified control system in which separate motors are employed for driving the blower and the fuel feed device.

Referring to Figure 1, a heating furnace of any suitable construction is indicated at 1, the furnace being provided with an ash-pit 1a, a combustion chamber 1b, and a flue 1c. A smoke pipe 2 connects the furnace with a chimney 3. Arranged within the lower part of furnace 1 is a coal burner consisting of a tuyère 4 arranged within a casing 5 which constitutes an air chamber surrounding the tuyère 4. The blower 6, driven by a motor 7, supplies air to chamber 5 through a duct 6a. The motor 7 is also arranged to drive suitable mechanism for transferring coal from a supply bin 8 to the tuyère 4 through a conveyor duct 8a. This mechanism usually involves a rotary screw conveyor located in the duct 8a, although other types of conveyors may be used.

The motor 7, which drives the fuel feed mechanism and the blower 6, is energized from a suitable electric supply circuit indicated at 9, and the operation of the motor is controlled by a thermostatic switch 10 in accordance with the temperature or heat demands of the space in which the switch 10 is located. Thermostat 10 is usually, but not necessarily, located in one of the first floor rooms. The motor 7 is preferably also energized at periodic intervals independently of the condition of the thermostat 10 by means of known control mechanism indicated at 11. This mechanism may assume various known forms. One suitable arrangement is shown in the patent to Gray et al. 1,667,001. It should be understood that the automatic control 11 need not be employed, and the motor can be controlled directly by the thermostatic switch 10, if desired.

The blower 6 is provided with an adjustable damper 6b arranged over the inlet port of the blower for controlling the amount of air supplied to the burner. The damper 6b is arranged to be operated by a time-delay device (indicated at 12) which becomes effective a predetermined time after the motor 7 begins to operate. This time-delay device may assume various forms, and three different constructions are shown in Figures 1a, 1b and 1c.

The time-delay device of Figure 1a is mounted in a suitable casing or frame 12a and consists of a worm gear 17 mounted on a shaft 17a which is driven from the motor 7, which supplies fuel to the furnace, preferably at a slow speed by means of a suitable speed-reducing gear, such as

by a gear 12b driven by a worm on the motor shaft. The thread on the worm 17 terminates at the top of the worm in a continuous groove 17b. A follower lever 18 is pivoted at one end on a pin 19 which is secured to the casing 12a and engages an elongated slot 18a in the lever. A tooth 18b is provided on the other end of the lever for engagement with the thread of the worm 17. A biasing spring 20 is provided to normally hold the lever 18 away from the worm as shown in the drawing, and a magnet 21, energized in parallel with the fuel-feeding motor, is arranged to attract armature 18c mounted on lever 18 and to shift the lever 18 so that the tooth 18b engages the thread on the worm 17. A link 22 is provided on the lever 18 for the purpose of operating any of the various air controlling devices shown in the drawing, such as operating the dampers 6b, 6c in Figures 1 and 2, or for controlling the circuit of the damper magnet in Figure 3, or for controlling the circuit of motor 1a in Figure 4. As shown in Figure 1, magnet 21 is connected in parallel with motor 7 by leads 21a.

It will be understood that as soon as the fuel-feeding motor is energized, magnet 21 causes engagement of the lever 18 with the worm 17. Rotation of the worm slowly raises the left end of lever 18 until it reaches the continuous groove 17b where it remains as long as the fuel-feeding motor is in operation. As lever 18 is raised by the worm, link 22 connected to the air controlling device opens damper 6b and increases the amount of air supplied to the burner. As soon as the fuel-feeding motor is de-energized, magnet 21 releases the armature 18c and lever 18 is retracted from engagement with worm 17 by spring 20, and the lever 18 then returns to its lower or starting position.

An adjustable stop 22a is secured to link 22 and serves to limit the downward movement of the link. By varying the position of stop 22a on link 22, the time of operation of the time delay device may be set at any desired value within certain limits.

In the operation of the arrangement shown in Figure 1, the mechanism 11 will energize the motor 7 at periodic intervals of short duration, so long as the space to be heated does not require any additional heat. This intermittent operation of the stoker is for the purpose of preventing the fire from dying out. As soon as the temperature of the space being heated falls below a definite limit, the thermostat 10 completes a circuit and causes operation of the stoker until the temperature in the space to be heated is brought back to normal. During the shut-down periods, the coal burns around the edge of the tuyère and leaves a ring of ash around the outer edge of the tuyère as indicated by the dotted area 4a in Figure 1, the hot spot of the fire 4b being located at the center of the tuyère. In the systems now commonly in use, the full blast of air is supplied to the air chamber 5 surrounding the tuyère 4 as soon as the motor 7 begins operation, and the ring of ash 4a is violently blown upwardly into the combustion chamber 1b, into the flue 1c and out the chimney 3. Some of the "fly-ash" filters through small cracks or openings around the doors of the furnace, or in the various joints, and is carried into other parts of the room. According to my invention, however, the damper 6b is normally set in a position such that the amount of air supplied to the air chamber 5 is insufficient to cause any substantial blowing

of the fly-ash from around the rim of the burner. Accordingly, by arranging for sufficient time delay in the operation of the damper-operating device after motor 7 begins to operate, the fuel-feeding mechanism will supply enough coal to the tuyère to displace the ash from directly over the air openings in the tuyère by the time the damper 6b is fully open and the full blast becomes effective. As soon as the air openings in the tuyère become covered with unburned coal, the force of the air stream is thereby cut down and there is no substantial blowing of the fly-ash.

The amount of air supplied to the burner may be controlled by a damper 6c located in the supply duct 6a as illustrated in Figure 2. It will be understood that the damper 6c is normally adjusted to supply a small amount of air to the burner, but insufficient to cause any substantial blowing of the fly-ash. The time-delay device 12 may be according to any of the constructions shown in Figures 1a, 1b and 1c. The dotted line 17a' represents the driving connection between shaft 17a and the shaft of fuel-supply motor 7.

Instead of having the time-delay device control the damper directly, the damper may be operated by an electromagnet 13, as shown in Figure 3, and the circuit of the electromagnet is controlled by a switch 22b operated by the link 22 of the time-delay device 12 which may assume the form of any of the devices shown in Figures 1a, 1b, and 1c.

In Figure 4, I have shown a modified control arrangement in which the motor 7 is employed for driving the fuel-feeding arrangement, and a separate motor 1a is provided for driving the blower. The motor 7 is controlled by the intermittent control device 11 in the same manner as in the other arrangements, and the motor 1a is energized by a circuit connected in parallel with the terminals of motor 7 through a switch 22b operated by time-delay device 12 which may assume any of the forms shown in Figures 1a, 1b, and 1c. In this arrangement, the motor 1 begins to operate and to supply fuel to the tuyère 4, and a predetermined time elapses before the switch 22b closes the circuit to the blower motor 1a. Accordingly, by adjusting the time delay of the device 12, the motor 1 will feed enough coal to the tuyère to displace the ash from above the air opening in the tuyère.

In Figure 1b I have illustrated a modified construction of time-delay device in which elements serving similar functions to corresponding elements in Figure 1a are indicated by like-reference numerals. In this arrangement, the worm 17 is mounted upon the shaft 17a which in turn is driven from the motor 7, the same as in Figure 1a. Instead of employing a pivoted lever for operating the link 22 by engagement with the worm 17, the link 22 in Figure 1b is secured to a sliding carriage 23 which is mounted for vertical sliding movement upon shaft 17a and upon rod 23a mounted parallel with the shaft 17a. Magnet 21 is mounted upon carriage 23 and a bell-crank armature 23b is provided for the magnet 21. A finger 23c, carried by the free end of the bell-crank lever is arranged to engage the thread on the worm 17 when magnet 21 is energized. The spring 20 normally biases armature 23b in a direction to disengage finger 23c from the worm 17. Adjustable stop 22a, mounted upon link 22, engages the lower wall of casing 12a and serves to limit the downward movement of carriage 23, and, as in the case of Figure 1a,

adjustment of the position of this stop effects adjustment in the time of operation of the time-delay device. The operation of Figure 1b is believed to be clear from the foregoing description of operation of Figure 1a.

In Figure 1c, I have illustrated a further modification of the time-control device which may be used in my invention. This device is somewhat like the arrangement shown in Figure 1a in that it employs a pivoted lever 18 to operate link 22 by engagement with the worm 17, but instead of employing a magnet to shift the lever 18 into engagement with the worm, I employ a centrifugal governor 24, driven from the shaft 17a for shifting the lever 18 into engagement with the worm 17, as soon as the motor 7 reaches a predetermined speed. The governor 24 may be of any suitable construction, and simply for the purpose of illustration, I have shown the governor as comprising the well known construction of pivoted arms, having weights attached thereto, mounted upon a shaft 24a which is driven from shaft 17a by means of worm gear 17b and worm 17c. Lever 18 is pivoted at one end to a point intermediate the ends of a second lever 18d, which in turn is pivoted at one end 18e to the supporting frame 12a. The opposite end of the lever 18d is provided with a fork which engages in the groove of movable collar 24b of the governor 24. Spring 20 normally biases lever 18d in a direction to disengage lever 18 from worm 17 when the shaft 17a is stationary or turning at a speed below a predetermined speed.

In the operation of the arrangement shown in Figure 1c, the shaft 17a, and, therefore, the governor 24, is driven at a speed proportional to the speed of the fuel-feeding motor 7. When the motor is first energized, the parts of the time-delay device are in the position shown in Figure 1c. The motor comes up to full speed rather quickly and the governor 24 moves the lever 18 into engagement with worm 17 and thereafter lever 18 travels upward in contact with worm 17 until it reaches the continuous groove 17b where it remains as long as motor 7 continues in operation. As soon as the motor 7 stops operating, governor 24 ceases to exert any pull on lever 18d and spring 20 withdraws the lever 18 from engagement with worm 17 and the parts are returned to the starting position shown in Figure 1c.

From the foregoing, it will be seen that in all forms of my time-delay device, the movable element 22 is mechanically driven by the fuel-feeding motor from a starting position to an operating position by means of the worm 17. Furthermore, in all three modifications, the driving connection between the motor 7 and the movable element 22 embodies a releasable clutch device which is normally open when the motor 7 is de-energized. The clutch device in each case is controlled according to an operating condition of the fuel-feeding motor. In Figures 1a and 1b the clutch device is controlled by magnet 21 in accordance with the voltage applied to the motor, while in Figure 1c the clutch device is controlled by governor 24 in accordance with the speed of the motor. In all three forms of the device the movable member 22 is normally biased by gravity to the lower or starting position, but springs may be used to supply the biasing force if desired. Motor 7 is preferably a constant speed motor, although no special type of motor is required.

My invention not only reduces and/or substantially prevents the blowing of fly-ash, but it also improves the efficiency of operation of the burner. This latter advantage is realized by reason of the fact that the full blast of air is not applied at the beginning of each period of operation, but is delayed until unburned coal covers all of the air openings in the tuyère. In this manner, the air blast is rendered completely effective for promoting combustion of the coal and none of the air is lost by passing through openings in the tuyère which is uncovered by reason of the ash having been blown away. Since there is no substantial amount of air wasted by passing through uncovered tuyère openings, the operation of the burner is more efficient, the temperature of the furnace rises quicker, and each operating period is correspondingly reduced.

What I claim is:

- 20 1. In combination, a solid fuel burner, intermittently operating means for supplying fuel to said burner, a blower for supplying air to said burner, a damper for controlling the flow of air to said burner normally arranged to restrict the flow of air to less than full blast, a worm driven by said fuel supply means, a follower operated by said worm, a connection from said follower to said damper for operating said damper, means for normally biasing said follower out of engagement with said worm, and means rendered operative upon starting said fuel supply means for moving said follower into engagement with said worm.
- 25 2. In combination, a solid fuel burner, means including a motor for supplying fuel to said burner, a blower for supplying air to said burner, a damper for controlling the flow of air to said burner normally arranged to restrict the flow of air to less than full blast, a movable element for opening said damper, driving means for mechanically operating said movable element from said fuel supply motor and including a normally open clutch element, and means responsive to an operating condition of said fuel supply motor for operating said clutch element.
- 30 3. A combination according to claim 2 wherein said clutch operating means comprises an electromagnet energized in parallel circuit relation with the fuel supply motor.
- 35 4. A combination according to claim 2 wherein said clutch operating means comprises a centrifugal governor driven by the fuel supply motor and adapted to operate said clutch when said motor reaches a predetermined speed.
- 40 5. In combination, a solid fuel burner, intermittently operating means including a motor for supplying fuel to said burner, a blower for supplying air to said burner, a damper for controlling the flow of air to said burner normally arranged to restrict the flow of air to less than full blast, a worm driven by said fuel supply motor, a follower operated by said worm, means for normally biasing said follower out of engagement with said worm, means rendered operative upon starting said fuel supply means for moving said follower into engagement with said worm, and means controlled by said follower for operating said damper to full draft position a predetermined time after the starting of said motor.
- 45 6. A combination according to claim 9 wherein said fuel supply means is driven by one motor and said air-supply means is driven by a separate motor, and including a normally open switch in the circuit of said air-supply motor, said switch being operated by said follower to close

the circuit of said air-supply motor a predetermined time after starting of said fuel supply motor.

7. In combination, a solid fuel burner, intermittently operating means for supplying fuel to said burner, means for supplying air to said burner, said air supplying means being normally ineffective to supply full blast of air, a worm driven by said fuel supply means, a follower operated by said worm, a connection from said follower to said air supplying means for controlling said air supplying means, means for normally biasing said follower out of engagement with said worm, and means rendered operative upon starting said fuel supply means for moving said follower into engagement with said worm.

8. In combination, a solid fuel burner, means including a motor for supplying fuel to said burner, means for supplying air to said burner, said air supplying means being normally ineffective to supply full blast of air, means including a movable element for controlling said air supplying means, driving means for mechanically operating said movable element from said fuel supply motor and including a normally open clutch element, and means responsive to an operating condition of said fuel supply motor for operating said clutch element.

9. In combination, a solid fuel burner, intermittently operating means including a motor for supplying fuel to said burner, means for supplying air to said burner, said air supplying means being normally ineffective to supply full blast of air, a worm driven by said fuel supply means, a follower operated by said worm, means for normally biasing said follower out of engagement with said worm, means rendered operative upon starting said fuel supply means for moving said follower into engagement with said worm, and means controlled by said follower for rendering said air supplying means operative to supply full blast of air to said burner a predetermined time after the starting of said motor.

10. A combination according to claim 9 wherein in said means for moving said follower into engagement with said worm comprises an electromagnet energized simultaneously with said fuel supply motor.

11. A combination according to claim 9 wherein in said means for moving said follower into engagement with said worm comprises a centrifugal device driven by said fuel supply motor.

ERNEST T. SELIG, JR.
